CLAIM

The ornamental design for a chart board, as shown and described.

DESCRIPTION

FIG. 1 is a perspective view of a chart board showing my new design;

FIG. 2 is a side elevational view in partial section taken on line 2—2 of FIG. 4;

FIG. 3 is a front elevational view;

FIG. 4 is a top plan view thereof at reduced scale;

FIG. 5 is a bottom plan view thereof; and

FIG. 6 is an enlarged scale fragmentary view of the left end of FIG. 2

FIG. 2**FIG. 6****FIG. 3****FIG. 4****FIG. 5**
